UNITED STATES PATENT OFFICE

JOHN C. HEBDEN, OF NEW YORK, N. Y., ASSIGNOR TO DYEING PROCESSES CORPORATION,
OF NEW YORK, N. Y., A CORPORATION OF NEW YORK

YARN HOLDER

Application filed January 9, 1926. Serial No. 80,316.

The present invention relates to improvements in yarn holders for supporting and retaining thereon in proper form yarn or similar textile material in the form of a 5 cop, spool, bobbin or cheese or other form of package during the process of dyeing or treating the yarn with a dyeing or other fluid.

One of the primary objects of the invention 10 is to provide a novel and improved pervious holder of this class wherein the surfaces thereof which support the yarn are of relatively small area with respect to the inner cylindrical surface of the opening in the 15 yarn, thus enabling the yarn on the holder to be compressed by the application of axial pressure at its ends, incident to the forming of fluid-tight connections for the dyeing or treating liquor to be forced through the yarn 20 during the dyeing or treating operation, whereby the dyeing or treating liquor will be caused to pass through the yarn in such manner as to insure uniform and level dyeing or other desired treatment.

Another object of the invention is to provide a previous holder of this class wherein 25 the surfaces thereof which support the yarn are straight and continuous or without interruption throughout the yarn engaging 30 length of the holder, so that no obstructing edges or openings exist in the surface, and, hence, the yarn which engages these surfaces will not catch thereon while the holder is being inserted into or removed from the 35 cop, spool, bobbin or cheese, or other form of package, but will pass into or out of the package substantially without friction and without injury to the yarn, thus facilitating the substitution of a paper, wooden or other 40 holder for the pervious holder, or vice versa.

Another object is to provide a novel and improved construction for a holder of this 45 general class whereby great strength and rigidity are attained, the surfaces which support the yarn or other material comprising longitudinal members, the ends of which are fixed and secured firmly by the clamping action produced and maintained between an outer member which is under tension and an 50 inner member.

Another object of the invention is to provide a pervious holder for yarns and other materials onto which the yarn or material may be transferred from a paper, wooden or other holder preparatory to dyeing or other 55 treatment, after which the yarn or material may be readily removed from the holder to a paper tube or a wooden or other substitute holder.

Further objects of the invention are to 60 provide a method whereby a previous holder of any suitable kind may be readily inserted in the yarn package as a substitute for a paper, wooden or other holder, thus facilitating the preparation of the yarn for dyeing or 65 other treatment, and to provide a method whereby a pervious holder may be readily inserted in the yarn package as a substitute for a paper tube or a wooden or other holder 70 preparatory to the dyeing or other treatment of the yarn, and after such dyeing or other treatment has been accomplished, the pervious holder may be easily and quickly removed 75 from the yarn package and a paper tube or a wooden or other holder inserted or substituted.

In the accompanying drawings:

Figure 1 is a side view, and Figure 2 is an end view of a yarn holder constructed in accordance with one embodiment of the invention.

Figure 3 is a detail collective view showing an end of one of the supporting members and a portion of the cooperating end ring of the holder shown in Figures 1 and 2.

Figure 4 is a side view, and Figure 5 is an end view of another yarn holder constructed in accordance with the present invention.

Figure 6 is a detail collective view showing the manner of mounting and securing the ends of the supporting members in a holder constructed as shown in Figures 4 and 5.

Figure 7 is a view showing the manner 95 of transferring a yarn package from a holder like that shown in Figures 4 and 5 onto a paper tube, or vice versa.

Figure 8 is a side view, and Figure 9 is an end view of a yarn holder constructed in 100

accordance with another embodiment of the invention.

Figure 10 is a detail collective view showing the manner of mounting and securing the supporting members in a holder as shown in Figure 8.

Figure 11 is a detail end view of the spacing and stiffening ring which is preferably employed in the holder shown in Figures 6, 8, 9 and 10.

Figures 12 and 13 are side and end views, respectively, and Figure 14 is a detail collective view, of another construction for the holder.

Figures 15 and 16 are side and end views, respectively, and Figure 17 is a detail collective view, of a further modification of the holders.

Similar parts are designated by the same reference characters in the several views.

The present invention provides a holder which is applicable generally to various uses where it is desirable to support a material during the handling thereof or the performance of operations thereon. The invention is especially applicable to yarn holders of the general class used in yarn dyeing machines to support the yarn while in wound form so that the dyeing liquor may be forced through the yarn to dye it, although such holders, it will be understood, may be used in other situations where materials of different kinds, especially textile materials, are to be supported in a manner to enable a treating fluid to be passed into or through them. The preferred embodiments of the invention are shown in the accompanying drawings and will be hereinafter described in detail, but it is to be understood that the invention is not restricted to the precise constructions shown as equivalent constructions are contemplated, and such will be included within the scope of the claims.

In the embodiment of the invention shown in Figures 1 to 3, inclusive, the holder comprises a suitable number of circumferentially spaced supporting members 1 which extend in parallelism longitudinally of the holder so that their outer or peripheral edges which are to serve as supporting surfaces for yarn or other material placed thereon coincide with the circumferentially spaced lines of a cylinder, the diameter of which substantially equals the diameter of the hole or bore in the package of yarn or material to be placed thereon. In order to secure lightness of weight and rigidity as well as to facilitate the manufacture of the holder, these supporting members are preferably constructed from strips of sheet metal which are folded or doubled transversely into channel form, the flanges of the supporting members when thus formed, serving to stiffen these members radially of the holder.

The supporting members are mounted and

secured at each end of the holder on an inner ring 2 which is preferably made of an endless band of metal of suitable thickness. This ring is provided with slots 3 which extend inwardly from its opposite edges and are located to properly receive the flanges of the supporting members. Preferably, the flanges of each supporting member are formed with tongues or lugs 4 which are adapted to enter the slots 3 in the inner ring and the flanges between these tongues are notched, as at 5, to receive the portions of the ring which intervene the slots 3. As shown in the present instance, the tongues 4 of two adjacent supporting members enter each pair of aligned slots 3 in the ring. The ends of the supporting members, at each end of the holder, are encircled by an outer ring or band 6 which may have an inturned flange thereon to partly overlie the ends of the supporting members, as shown. The parts of the holder are so constructed and assembled that the ends of the supporting members will be firmly held by a clamping action produced between the inner ring 3 and the outer ring 6, which latter is under tension and has a tendency to contract. This clamping action may be produced by expanding, by a tube expander, or other means, the inner ring 3. After all of the parts of the holder have been assembled, the resulting expansion of the ring 3 forcing the ends of the supporting members outwardly against the outer ring 6, thus putting the latter under tension, so that it exerts a compression on the inner ring.

In this construction, the slotted inner rings in cooperation with the tongues on the supporting members secure the supporting members in proper circumferentially spaced relation and prevent relative endwise displacement of any of the supporting members with respect to these rings, and the compression of the ends of the supporting members between the inner ring, and the outer ring, which is under tension, and tends to contract, binds the supporting members firmly in position and avoids the development of looseness, which, if permitted to occur, would result in relative displacement of the supporting members or other parts of the holder.

In using a holder constructed as just described the yarn in wound or package form may be transferred from a paper, wooden or other holder onto the holder shown by pushing the package axially over one of the outer rings 6, and this may be done without difficulty by making the outer diameter of the rings 6 equal to the diameter of the paper, wooden or other holder from which the yarn package is to be transferred. Holders as described, and on which yarn packages have been placed, may be mounted in a dyeing machine of any type suitable for the dyeing of yarns, and the ends of the yarn packages on the holders may be engaged by ele-

ments of the machine which exert axial compression on the yarn package and thereby form fluid-tight joints to enable the dyeing liquor to be forced through the package of 5 yarn. The compression to which the yarn packages are thus subjected does not interfere with the uniform dyeing of the yarn as the yarn on each holder is engaged only by the limited areas formed by the edges of the 10 circumferentially spaced supporting members so that the dyeing liquor may flow freely through the central interior axially extending chamber or passageway formed within the circular series of supporting members, 15 then outwardly through the spaces between the supporting members and through the package of yarn, or vice versa, substantially without obstruction by the supporting members.

20 Holders constructed as shown in Figures 1 to 3, inclusive, may be used advantageously in the dyeing or other treatment of packages of yarn and other textile materials, but after the packages of yarn have been dyed or 25 treated on such holders, the yarn cannot be removed therefrom unless by unwinding. Figures 4, 5 and 6 illustrate another embodiment of the invention whereby removal of the yarn packages from the holder after dyeing or treatment, as well as insertion of the 30 holder into the package, may be accomplished quickly and with facility and without the necessity of unwinding the yarn. In this embodiment of the invention the holder comprises a suitable number of supporting members 6 which are suitably spaced circumferentially of the holder and extend in parallelism longitudinally thereof, they thus forming a central interior chamber or passageway 35 within the holder, the outer edges of these supporting members coinciding with lines extending axially of a cylinder, the diameter of which approximately equals the hole or bore of the packages of yarn which the holder 40 is to receive. These supporting members, as in the preceding instance, are preferably formed of strips of sheet metal doubled or folded transversely to secure strength and lightness in weight, and the ends of the supporting members are firmly and immovably 45 held by a clamping action produced and acting between an inner ring 7 and an outer ring 8 which is under tension and tends to contract. Preferably, the flanges of each supporting member are extended, as at 9, and bent and formed to fit against the inner ring 7, or, as shown, one of these flanges fits directly against the inner ring 7 while the other flange of each supporting member overlaps 50 or bears against the outer side of the flange of the next adjacent supporting member. The flanges of the supporting members are formed with slots 10 which extend inwardly from their ends to receive the outer ring 8, 55 these slots being preferably so located that

the outer ring 8 will bear directly against the outer or overlapping flanges 9 of the supporting members. After the supporting members have been assembled with the inner and outer rings 7 and 8 in proper position at both ends of the holder, each of the inner rings 7 is expanded by a tube expander or other suitable implement until the outer ring 8 has been put under tension. The ends of the supporting members will be firmly compressed and thus held between these two rings.

70 A previous holder constructed as shown in Figures 4, 5 and 6 may be directly inserted into a package of yarn or other material by pushing the package of yarn from a paper tube 11 or other suitable holder of the same diameter as the previous holder onto the previous holder, and after the dyeing or other treatment has been performed, the package of yarn or other material may be transferred 80 from the previous holder onto a paper tube as the tube 11, or onto a wooden or other desired holder by endwise displacement of the package, these operations being represented in Figure 7. The insertion and removal of the previous holder as described is made possible by constructing the supporting members so that they extend in parallel straight lines continuously or without interruption throughout the length of the holder so that there are no edges or other obstructions upon which the yarn might catch. In order to insure proper registration between the previous holder and the paper tube or other holder from or to which the package is to be transferred, the mandrel of the paper tube or the wooden holder may have a stem 12 thereon which is located concentrically with its axis and is of a diameter to closely fit into the inner ring 7 of the previous holder.

90 The present invention provides also a method whereby a paper tube or a wooden or other holder may be removed from a package of yarn or other material and a previous holder of any of the types heretofore used may be inserted into the package preparatory to dyeing or other treatment thereof, without the necessity of unwinding and rewinding the yarn or other material. This is accomplished 100 by the use of a paper tube such as the tube 11, Figure 7, or a wooden or other holder upon which yarn is wound, which tube or holder has a diameter substantially equal to that of the previous holder which is to receive the package, the previous tube being placed with one of its ends against and centered coaxially with the paper tube or wooden holder, and while the two holders are in such relation, the previous holder is pushed into the package and coincidently the paper tube or wooden holder is pushed out of the package, the package of yarn being thus transferred from the paper tube or wooden holder to the previous holder without the necessity of prelimi- 105

75

80

85

90

95

100

130

narily winding the yarn onto the previous holder.

Figures 8 to 11, inclusive, illustrate another embodiment of the holder wherein the supporting members 13, which extend parallel to and are suitably spaced circumferentially of the holder and form a central interior axially extending chamber of passageway within them are constructed from strips of sheet metal doubled or folded transversely to give them a channel form in cross-section, but the ends of the supporting members are drawn or formed into terminal flanges 14 which are curved to fit against the outer circumference 15 of an inner ring, and these terminal flanges of the supporting members are encircled by an outer ring 16 which, in this instance, is smaller in diameter than that of a cylinder which includes the yarn-supporting edges of the supporting members. After the terminal flanges of the supporting members have been assembled, so that they lie between the inner and outer rings 15 and 16, the inner ring 15 is expanded by a tube expander or other suitable implement until the outer ring 16 has been put under tension. The terminals of the supporting members will then be secured firmly by the clamping action produced by the outer ring which is under tension and tends to contract upon the inner ring.

The intermediate portions of the supporting members in this embodiment of the invention, as well as in the other embodiments thereof herein described, may be stiffened by a reinforcement which will assist the supporting members in sustaining compression exerted on their yarn-supporting surfaces, and will maintain the intermediate portions of the supporting members in proper circumferentially spaced relation. As shown in Figures 10 and 11, this reinforcement may consist of a ring 17 which may be made of sheet metal of appropriate thickness and having bends 18 formed therein at points in its circumference which correspond with the circumferential spacing of the supporting members of the holder, so that when the supporting members are assembled, each supporting member will straddle or receive one of these bends 18 of the reinforcement, as will be clear from Figure 10. The reinforcing ring will thus serve to connect the intermediate portions of the supporting members and thus assist them in sustaining compression forces acting thereon as well as forces tending to bend or deflect them out of parallelism. In order to prevent displacement of the reinforcing member in a direction longitudinally of the holder, the inner edges of the flanges of the supporting members may be notched, as indicated at 19, to receive the reinforcing ring.

In this form of holder, the package of yarn may be readily transferred therefrom onto a

paper tube, wooden bobbin or other substitute holder by pushing the yarn endwise, as there are no portions of the holder larger in diameter than that of the supporting members, so that removal of the yarn past the ends of the holder will not be obstructed.

Figures 12, 13 and 14 illustrate another construction of holder similar to that shown in Figures 1, 2 and 3 but which enables it to be removed from as well as inserted into the package of yarn without requiring unwinding or rewinding of the yarn. In this instance, the ends of the supporting members 1a are formed like those shown in Figure 1, the lugs 4a thereon entering notches 3a in the inner ring 2a while the spacing recess 5a between the lugs receives the portion of this ring which intervenes the notches 3a, but the outer ring 6a, instead of extending around the outside of the supporting members, is fitted into slots 1b formed in the ends of the supporting members. By this construction, the outer ring does not obstruct the endwise movement of the yarn package along the edges of the supporting surfaces or in other words, the yarn-engaging surfaces of the supporting members are straight and continuous or uninterrupted throughout their lengths, and hence the holder may be inserted axially into and removed from the yarn package without obstruction and substantially without friction, thus avoiding the necessity of unwinding or rewinding the yarn prior or subsequent to its dyeing or other treatment. The ends of the supporting members may be secured by the clamping action exerted upon them by the contacting tendency of the outer ring, as in Figure 1.

In the construction shown in Figures 15, 16 and 17, the supporting members 13a which form a central interior axially extending chamber or passageway within the holder are similar to those shown in Figures 8, 9 and 10, the ends thereof being so shaped that they merge from the channel form into relatively flattened but arcuate portions of a radius to conform with the outer periphery of the inner ring 15a so that the ends of the supporting members will seat closely against the inner ring. The longitudinal edges of these arcuate portions, however, are formed with lugs 20 which are turned inwardly, and the inner ring is formed with notches 21 in its opposite edges to receive these lugs, the edges of the arcuate portions having recesses 22 between the lugs to receive the portions of the inner ring which intervene the notches 21. Relative endwise displacement of the supporting members and the inner ring is thus effectively prevented. The outer ring 16a cooperates with the inner ring 15a to secure the ends of the supporting members, expanding of the inner ring as previously described, producing a clamping action between the

rings which firmly secures the supporting members in place.

Holders embodying the present invention may be used for various purposes but they are particularly adapted to hold packages of yarn in proper form and condition to enable the yarn to be dyed. These holders having the packages of yarn thereon may be placed in any suitable dyeing apparatus of the general class employed for this purpose, an example of a dyeing apparatus suitable for the purpose being shown and described in Letters Patent No. 1,052,817, granted February 11, 1913, the ends of each yarn package receiving axial pressure acting in opposite directions, as, for example, by compressing the package endwise between elements of the apparatus to form fluid-tight connections at these points which will cause the circulating dye liquor to pass either from the center outwardly through the yarn or vice versa. The axial compression thus imposed on the package will not hinder or interfere with the proper passage of the dye liquor through the yarn as the yarn will be compressed uniformly, and, moreover, the yarn supporting surfaces on the holder are of such relatively small areas that the flow of the dye liquor through the holder and between the holder and the yarn is not appreciably impeded. Furthermore, the holder is incompressible axially so that axial compression of the yarn thereon may take place without interference by the holder and the nature of the engagement of the yarn with the holder is not altered. In consequence, the yarn during the dyeing operation, is held in such condition as will insure uniform and thorough dyeing of the yarn.

By providing the holder with yarn-engaging surfaces which are straight and continuous or without interruption throughout the length of the holder, the operation of inserting the holder into the yarn package or removing the holder therefrom may be performed easily and quickly and without damage to the yarn. The continuous or uninterrupted nature of these yarn-engaging surfaces does not become disturbed during the use of the holder, especially as the holder is not compressible or expandable axially, or otherwise deformable in a manner that would resist or prevent its insertion into or removal from the yarn.

The ends of the supporting members are so secured at the ends of the holder as to insure proper spacing of said members. By securing the ends of the supporting members by a clamping action produced by the contracting tendency of the outer ring, permanence in the securing of the parts of the holder is attained, there being no opportunity for the parts to become loose relatively to one another as the inherent elasticity of the inner and outer rings while under stress will compensate

for any changes which would otherwise tend to cause looseness between the parts of the holder.

I claim as my invention:—

1. A pervious holder of the class described comprising a series of circumferentially-spaced axially extending supporting members, and inner and outer rings at each end of the holder, said rings confining the ends of the supporting members between them. 70

2. A pervious holder of the class described comprising a series of circumferentially-spaced axially extending supporting members, and means abutting the ends of said members at their inner sides and means abutting the ends of said members at their outer sides to clamp said members together. 80

3. A pervious holder of the class described comprising a series of circumferentially-spaced axially extending supporting members, and inner and outer rings cooperative with the ends of said members, the ends of said members being interposed between and held by the compression exerted upon them by said rings. 85

4. A pervious holder of the class described comprising a series of circumferentially-spaced axially extending supporting members of channel form in cross-section, means for supporting said members at their ends, 95 and a bracing ring arranged within the series of supporting members and having projections thereon which enter the channels thereof.

5. A pervious holder of the class described comprising a series of circumferentially-spaced axially extending supporting members, a ring arranged within the ends of said members, the ends of said members having arcuate portions which bear against the inner ring, and an outer ring which encircles the arcuate ends of said members and cooperates with the inner ring to secure them. 100

6. A pervious holder of the class described comprising a series of circumferentially-spaced axially extending supporting members formed of sheet metal doubled substantially into channel form, the flanges of the members being directed inwardly and the doubled portions of said members presenting yarn-engaging surfaces on the periphery of the holder, the ends of said members being bent inwardly and curved in arcs of a circle, and annular means cooperative with the arcuate ends of said members for securing them. 110

7. A pervious holder of the class described comprising a series of circumferentially-spaced axially extending supporting members formed of sheet metal doubled substantially into channel form, the ends of said members being of arcuate form, an inner ring with which said arcuate portions conform and against which they fit, and an outer ring encircling the arcuate portions of the sup- 125

porting members and cooperative with the inner ring to secure them in place.

8. A yarn holder made up of a plurality of circumferentially spaced axially extending parallel ribs joined together to form a skeleton cylinder having a central hollow axially extending chamber open at each end of said holder.

In testimony whereof I have hereunto set
10 my hand.

JOHN C. HEBDEN.
